UNITED STATES PATENT OFFICE.

JOHN LANGAN, OF PORTLAND, OREGON.

DISAPPEARING BED.

1,147,028.

Specification of Letters Patent. Patented July 20, 1915.

Application filed June 8, 1914. Serial No. 843,642.

To all whom it may concern:

Be it known that I, JOHN LANGAN, a citizen of the United States, residing at Portland, in the county of Multnomah and State 5 of Oregon, have invented certain new and useful Improvements in Disappearing Beds, of which the following is a specification.

This invention relates to improvements in disappearing beds and has for its object 10 to provide means for folding a bed, mattress and bed clothes within a cabinet for the purpose.

Another object is to provide a folding and disappearing bed adapted to its purpose 15 without the necessity of the usual bed-clothes clamps.

These objects are attained by means of the improvements herein specified and illustrated in the accompanying drawings, in 20 which:—

Figure 1 is a perspective view of the bed and cabinet, showing the bed lowered into position for use. Fig. 2 is a front elevation of the cabinet with the bed folded inside 25 and the bed clothes and mattress removed. Fig. 3 is a detail view in perspective of the bed frame and shows the hinged sides, leg-supporting rods, legs and leg braces. Fig. 4 is a sectional side elevation of the cabinet 30 with the bed folded inside and is taken on A—A in Fig. 2.

Referring to the drawings, 1 indicates a cabinet divided by shelves into three compartments, as at 2, 3, and 4, of which the 35 upper compartment 2 and the lower compartment 4 are intended for wearing apparel, linen, and bed pillows, as at 5. The large intermediate compartment 3 is intended to receive the folded bed frame and 40 bed clothes.

A door 6 is hingedly attached to the cabinet at 7 for the purpose of closing it and is provided with a clothes-bar 8 upon which garments may be hung for the purpose of 45 inclosing them within the cabinet. If desired, casters may be provided for the support of the cabinet, as at 10.

At 9 is provided a pivot rod horizontally disposed within compartment 3 and extending 50 from side to side of the cabinet to which it is attached. The bed frame is preferably constructed of metal, as indicated at 11, but could be made of wood if desired. It will be noted that the bed frame 11 is shown in

two sections which are hingedly attached, 55 one to the other, at 12, and provided with metal slats 13 having bent-over ends 14 by which they are attached, as by rivets, to the bed frame.

Leg-carrying rods 15 are transversely disposed between and rigidly fastened to the sides of the bed-frame 11 and carry at each end, adjacent the bed-frame, a bed-supporting leg 16 which is pivotally mounted and held against sliding upon said rod by cotter-pins 17.

Leg braces 18 having their upper ends disposed at right angles are pivotally mounted in bearings 19 on the frame 11, as shown in Fig. 3, and are provided with angularly bent 70 lower ends 20, having a slight side projection as shown at 21.

A staple 22 is rigidly attached to each leg intermediate of its ends for the reception of the ends 20 of the aforesaid braces, the projections 21 tending to keep the braces from going through the staples too far. The length of the braces and their proper disposition are determined by the location of the staples, so as to hold the legs in vertical 80 position when the bed is lowered for use. Pins 23 are keyed into the upper ends of the braces to prevent them from sliding out of their bearings 19.

By referring to Fig. 1, it will be seen that 85 the forward section of frame 11 is provided with 4 legs and the rear section with 2 legs, the rear end of the rear section being supported within the cabinet by the pivot rod 9 upon which it is pivotally mounted, so 90 that it may be swung upwardly into the position shown in Fig. 4, in which a mattress and bedding 24 are shown as carried by the bed-frame. To facilitate manipulation of the bed for the purpose of folding 95 it within the cabinet, a lifting weight 25 is attached to a cable 26 which is fastened to the bed frame near one of the hinges at 28, and passes over a pulley 27 in such manner that the weight is carried within and near 100 the rear of the cabinet, the lower shelf or floor of compartment 3 being cut out to permit the weight to drop through into compartment 4.

It is obvious that various alterations may 105 be made to conform with the requirements of the bed, without deviating from the spirit of the invention, as for instance, two weights

and cables could be used for large beds and if desirable, springs may be used beneath the mattress.

Having described my invention, what I claim is:

- 5 1. A disappearing bed comprising a bed-frame built in two sections hingedly attached to one another, means for pivotally carrying the free end of one of the sections, 10 rods carried by the bed frame and extending between and from side to side, legs pivotally mounted on said rods, staples carried by the legs intermediate of their ends and brace bars pivotally mounted on the bed-frame and having an angularly bent end with a side projection near said end, so that the end may enter the aforesaid staple up to the side projection for the purpose of locking the legs in supporting position.
- 15 2. A disappearing bed comprising in combination a cabinet, a bed frame consisting of two sections hingedly attached to one

another and having the free end of one of said sections pivotally supported in said cabinet, said sections being adapted to fold 25 upwardly at the hinged ends and to swing back into said cabinet, and means extending from the upper part of said cabinet and attached to said bed sections near the hinged ends thereof and operating to pull said 30 hinged ends upwardly and back into said cabinet, said bed frame sections being provided at their hinged ends with supporting legs pivotally attached and adapted to swing in parallel relationship with each other into 35 the bed frame sections at opposite sides of the hinge joint, substantially as shown and described.

In testimony whereof, I affix my signature in presence of two witnesses.

JOHN LANGAN.
